DESIGN FOR A GLASS BOTTLE

Lawrence J. Kihm, Pittsburgh, Pa., assignor to J. T. & A. Hamilton Company, a corporation of Pennsylvania

Application April 5, 1940, Serial No. 91,494

Term of patent 7 years

to all whom it may concern:

Be it known that I, Lawrence J. Kihm, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part hereof.

In the accompanying drawing Fig. I is a front elevation of a glass bottle showing my new design; Fig. II is a fragmentary rear elevation of the said glass bottle; and Fig. III is a bottom plan view of the said glass bottle.

I claim:

The ornamental design for a glass bottle, substantially as shown.

LAWRENCE J. KIHN.
